United States Patent Office

Des. 196,529
Patented Oct. 8, 1963

196,529

STAMP AFFIXER

Irving S. Moser and Kurt Kulka, Houston, Tex., assignors
to Kim Manufacturing Corp., a corporation of Texas

Filed Oct. 11, 1961, Ser. No. 67,045

Term of patent 14 years

(Cl. D52—1)

Fig. 1

Fig. 2

Fig. 3

Fig. 4

Fig. 5

FIGURE 1 is a front elevational view of a stamp affixer embodying our new design;

FIGURE 2 is a right side elevational view thereof;

FIGURE 3 is a top plan view thereof;

FIGURE 4 is a back elevational view thereof;

FIGURE 5 is a left side elevational view thereof; and

FIGURE 6 is a bottom plan view thereof.

The diagonal lines seen in the stripe in FIGURE 1 represent an area of colored contrast.

We claim:

The ornamental design for a stamp affixer or the like, substantially as shown and described.
